Attorney

UNITED STATES PATENT OFFICE.

CHARLES F. NOLL, OF SISTERSVILLE, WEST VIRGINIA.

ADVERTISING DEVICE.

Application filed December 12, 1921. Serial No. 521,918.

To all whom it may concern:

- Be it known that I, CHARLES F. NOLL, a citizen of the United States, residing at Sistersville, in the county of Tyler and the State of West Virginia, have invented certain new and useful Improvements in Advertising Devices, of which the following is a specification, reference being had to the accompanying drawings.
- 10 This invention relates to advertising devices and has for its object to provide a device of this character which may not only be used for advertising purposes, but as a time table.
- 15 It is another object of the invention to provide a device of this character including a frame or cabinet which is relatively shallow or of a thickness to receive flat articles, such as cards, pictures, time dials, etc., so that the device when in use will occupy a small space.

It is also an object of the invention to provide a device of this character wherein the inner wall of the frame or cabinet is provided with a fabric lining which serves as supporting means for advertising matter disposed within the cabinet or frame, said advertising matter being provided with means adapted to penetrate the fabric to suspend the articles within the frame.

It is a further object of the invention to provide an advertising device of this character in the form of a shallow cabinet or frame wherein any part of the device may be used and arranged in various positions, as no individual frames for the advertising matter or devices is necessary.

It is a further object of the invention to provide an advertising device of this character, including a frame having a transparent door adapted to be inserted within the frame, said door being provided with means for detachably connecting the same to the frame.

45 With these and other objects in view, the invention consists in the improved construction and arrangement of parts to be herein-after more particularly described, fully claimed and illustrated in the accompanying drawings, in which:—

Figure 1 is a front elevation of an advertising device constructed in accordance with an embodiment of the invention;

55 Figure 2 is a longitudinal sectional view of the structure shown in Figure 1;

Figure 3 is a rear view of one of the ad-

vertising articles showing the application of the pivoted prongs;

Figure 4 is a rear elevation of one of the time dials, showing the application of the pivoted prongs;

Figure 5 is a detailed view of one of the pivoted prongs;

Figure 6 is a detailed view of the connecting means of the door to the frame; and

Figure 7 is a detailed view of the means for fastening the U-shaped prongs to the dials.

Referring to the drawings, 5 designates a frame or cabinet comprising a top member 6, a bottom member 7, and side members 8 and 9, substantially rectangular in cross section. The ends of each member are beveled and adapted to be connected to each other to substantially provide a frame.

A back 11 is secured to the face 12 of each member, the back cooperating with the frame to provide a cabinet which is rather shallow so that it will only occupy a small space when hung on the wall. Extending over the outer face of the back 11 is a sheet of fabric 13, such as velveteen, of any desired color, said fabric serving as a background for the device. The edges 14 of said fabric are secured to the marginal edges of the back 11, the fabric sheet being, of course, stretched across said face so as to lie perfectly smooth, but at the same time is not secured in any manner to the area of the face of the back within the edges of the back. The purpose of this is to permit the sheet to serve as supporting means for advertising matter to be placed within the cabinet or frame.

In connection with the cabinet, a door is used, said door comprising a frame 15, said frame being adapted to fit within the frame so that the outer face of the frame 15 is flushed with the outer surface of the parts 6, 7, 8 and 9. This feature assists in rendering the device compact. The inner face of the frame adjacent the opening in the frame is provided with a channel or groove adapted to receive the edges of a pane of glass 16, said pane being secured to the frame in any suitable manner. Extending around the inner face of the door 15 is a strip of padding 17, such as felt, said padding serving to prevent the entrance of dust when the door is closed. In order to connect the transparent door to the frame or cabinet, a plurality of hinges

18 are provided, each hinge comprising a plate 19 having knuckles 20 projecting from each end thereof in spaced relation to each other, the plate 19 having openings 21 for the reception of screws. The remaining section of the hinge comprises a relatively small plate 22 having a knuckle 23 extending longitudinally of one edge of the plate, said knuckle being disposed between the knuckles 20. A pintle 24 is used to pivotally connect the sections of the hinge to each other. One of the plates of each hinge is secured to the inner face of the members 8 and 9, while the remaining hinge is secured to the adjacent outer face of the door 15. Two pair of hinges are disposed adjacent the top of the frame and two pair of hinges are disposed adjacent the bottom, so as to balance the design of the frame 20 and at the same time permit the door to be readily opened by the removal of the pintles. It is only necessary, however, to open the door in order to change or rearrange the advertising matter.

25 In connection with the frame and the fabric sheet 13 novel advertising means are used in the form of cards or pictures 25 and time dials 26. It is of course obvious that any advertising device that is flat or relatively thin may be disposed within the frame. Each of the cards or pictures are held within the frame by means comprising a pair of prongs or pins 27, said pins being relatively long and having their upper ends 27^a extended laterally and formed into an elongated loop 28, said loop also extending laterally of the pins. A hinge composed of fabric 29 is provided, said fabric including a slot 30 which extends inwardly of one end and an extension or tab 31 which projects from the opposite end. In attaching the pin to the advertising card or picture, the pin is inserted through the fabric at the junction of the extension with said fabric 29, the extension 31 being passed through the loop 28 and the fabric then passed over the top of the loop. The portions of the fabric sheet on each side of the slot 30 are then secured to the rear face of the card by adhesive means, the shank of the pin extending through the slot 30. By this means, it is possible for the pin to be secured to the advertising matter without requiring the card to be punctured, which would interfere with the advertising matter on the front face thereof.

50 The dials 26 are intended to indicate train time, the hands 32 of the dials being secured to the central portion by means of eyelets 33. A U-shaped or double prong 34 is provided for connecting the dials to the casing, the bight portion of said U-shaped prong being secured to the rear face of the dial by a sheet of fabric 35, said fabric being formed

substantially T-shaped, the prongs of the fastener being adapted to extend through the wide portion of the fabric, as shown in Figure 7. Said wide portion of the fabric is then folded over the bight portion of the prongs and the narrow portion of the fabric extended over the wide portion, said fabric being then secured to the back of the dial as shown in Figure 4, by adhesive material, so that the pin is securely fastened.

55 From the foregoing it will be readily seen that this invention provides a novel advertising device which is very compact as the casing is shallow and the advertising matter relatively thin. Furthermore, by the use of the time dials, the advertising device 80 is made more attractive, as persons endeavoring to ascertain the train time cannot help but read the advertising matter on the cards disposed adjacent the time dials. It is of course obvious that I do not desire to limit myself to the use of cards or time dials, as it is possible to suspend articles within the casing, such as collars, with the use of the novel form of supporting prongs, neither do I wish to be limited to the precise arrangement of the time dials as they may be arranged to suit the purpose of the user. At the same time, by the use of the novel form of prongs, there is no danger of the advertising matter falling out of the casing when the door is removed. The glass pane of the door also assists in holding the cards and dials in position within the cabinet. This device will be found useful not only in depots but in hotels, theaters, and like public places, and all of these features are possessed by a device that is compact and simple in construction.

60 What is claimed is:—

1. A display device of the character described comprising a supporting member having the face thereof covered with a sheet of fabric, the fabric being unsecured to the support except at its margins, and devices to be displayed having prongs operatively connected thereto and adapted to be detachably inserted into said fabric.

65 2. The combination with an article to be displayed, of means for supporting the article comprising a strip of fabric having a perforation at one end, a pin inserted through said perforation and having a portion on the back of the fabric strip larger than the perforation, the fabric strip being folded over the head of said enlarged portion of the pin and caused to adhere to the back of the article to be displayed and whereby to provide a prong by which the article may be supported.

70 In testimony whereof I hereunto affix my signature.

CHARLES F. NOLL.
